CLAIM

The ornamental design for a banquette, as shown and described.

DESCRIPTION

FIG. 1 is a front perspective view of a banquette according to the first embodiment of my new design;

FIG. 2 is a front view thereof;

FIG. 3 is a rear view thereof;

FIG. 4 is a left side view thereof;

FIG. 5 is a top view thereof

FIG. 6 is a front perspective view of a banquette according to the second embodiment of my new design;

FIG. 7 is a front view thereof;

FIG. 8 is a rear view thereof;

FIG. 9 is a left side view thereof; and,

FIG. 10 is a top view thereof.

Features shown in broken lines form no part of the claimed design.
